PERCUSSIVE DRILL

Filed Feb. 24, 1928

UNITED STATES PATENT OFFICE

LOUIS W. GREVE, OF CLEVELAND, OHIO, ASSIGNOR TO THE CLEVELAND ROCK DRILL COMPANY, OF CLEVELAND, OHIO

PERCUSSIVE DRILL

Application filed February 24, 1928. Serial No. 256,614.

The present invention is directed to improvements in percussive drills of the valveless type.

The primary object of the invention is to provide a device of this character so constructed that a relatively large supply of motive fluid will be maintained in the rear of the large head of the differential piston for action thereon to more effectively move the same on its forward or working stroke, the same fluid also aiding in cushioning the piston on its rearward stroke.

Another object of the invention is to provide a device of this kind which will deliver a powerful working blow, and one which is simple in construction, efficient in operation, durable, and which will operate with a minimum amount of fluid.

With these and other objects in view, this invention resides in the novel features of construction, formation, combination and arrangement of parts to be hereinafter more fully described, claimed, and illustrated in the accompanying drawing, in which:—

25 The figure represents a longitudinal sectional view through the device.

Referring to the drawing, 1 designates the back head of a percussive drill and 2 the cylinder which is coupled thereto in any approved manner. Interposed between the front head 3 and the cylinder 2 is a tappet case 4 having associated therewith the tappet 5 for striking the drill steel 5'.

The cylinder 2 is formed with front and rear piston chambers 6 and 7, respectively, the former being of greater diameter than the latter, the purpose of which will be later explained. The rear end of the smaller piston chamber opens into a distributing chamber 8 which is formed in the back head 1, motive fluid being conducted thereto through the passage 9 leading from a source of compressed air. The back head is further provided with a centrally located pocket 10 which opens into the chamber 8, the purpose of which will later appear.

Mounted for reciprocation in the cylinder is a piston 11 which consists of a large head 12 slidable in the large chamber 6 and a smaller elongated head 13 slidable in the

chamber 7, the latter head being of such length that on its rearward stroke the rear end thereof will enter the distributing chamber 8 and also the pocket 10.

The heads 12 and 13 are connected by a reduced neck 14 which produces an annular groove 15 between the respective heads.

In the rear end of the chamber 6 is formed an annular chamber constituting a reservoir 16 in which a relatively large supply of motive fluid is stored for acting against the rear face of the head 12.

A longitudinally extending motive fluid conducting passage 17 is formed in the cylinder wall and connects with the front end 65 of the piston chamber 6 through a port 18, while the rear end of said passage connects with the rear end of the chamber 7 through the port 19, said passage also being in communication with the reservoir 16 through a 70 duct 20 which opens near the rear wall of said reservoir.

The cylinder wall is further provided with a relatively short passage 21 which has its rear end opening into the constant air chamber 8, the forward end thereof connecting with the forward end of the chamber 7 through the duct 22. The cylinder 2 is provided with an exhaust port 23.

As shown in full lines in the drawing, the piston is in its forward position and is about to begin its rearward stroke, and at which time the small head has uncovered the port 19 in order that motive fluid from the chamber 8 will pass therethrough into the passage 85 17 and through the port 18 to act upon the front face of the large head 12 to force the same rearwardly and against the pressure upon the rear end of the small head 13. Obviously some motive fluid will pass through 90 the duct 20 to maintain a supply of motive fluid in the reservoir 16 in order that a relatively large volume of motive fluid will be present to act against the rear face of the head 12, this same fluid also aiding in 95 cushioning the rearward movement of the piston. A flow of fluid through aperture 20 from the passage 17 is caused by and takes place when a back pressure is built up in the passage 17 as the incoming motive fluid fills 100

the end of the cylinder beneath the piston head 12. As the piston head 12 travels in its return stroke it covers the exhaust passage 23 and then the opening 7 into the passage 17. The motive fluid introduced into the cylinder above the piston through the orifice 20 aids in cushioning the return stroke of the piston. As soon as the opening 7 is closed by the end 11 of the piston the flow of fluid through passage 17 from the supply ceases, and the flow of fluid from the passage 17 through duct 20 into the cylinder ceases and reverses. The continued rearward travel of the piston compresses the fluid within the cylinder above the piston and causes fluid to flow thru the orifice 20, passage 17, orifice 18 and exhaust passage 23. The rate at which the fluid is so exhausted from the upper end of the cylinder is controlled very largely by the dimensions of the orifice 20, which may be such as to regulate the return motion of the piston at the desired rate. When the piston is moved in a forward direction the motive fluid introduced through passage 22 into the adjacent end of the cylinder, escapes, to a small degree, through duct 20, passage 17 and orifice 18 through the lower end of the cylinder. Even after the passage 21 has been closed by the end 13 of the piston the motive fluid in highly compressed condition in the upper end of the cylinder causes a flow of the fluid into the forward end of the cylinder where it aids in cushioning the piston 12. The rate of that fluid flow is determined by the size of the orifices 20 and 18. As the piston continues to move rearwardly the small head will close the port 19, thus cutting off the supply of motive fluid to the front face of the head 12, exhaust taking place through the port 23. Continued rearward travel of the piston will bring the neck 14 into the chamber 7 in order that the annular groove 15 will register with the duct 22, and at which time the rear end of the head 13 will enter the pocket 10, trapping motive fluid therein, which co-operating with the motive fluid in the reservoir 16 will effectively cushion the rearward movement of the piston to prevent the rear end of the head 13 striking the back head. When the groove 15 registers with the duct 22, as shown in dotted lines, motive fluid from the chamber 8 flowing through the passage 21 will enter the reservoir and act upon the rear face of the head 12 to drive the same forwardly, whereupon the rear end of the head 13 will be subjected to the pressure of the motive fluid in the chamber 8 when said rear end leaves the pocket 10. In this manner the full cross sectional area of the piston 11 is subjected to pressure in order that the same will be driven forwardly rapidly to strike the tappet a sharp and hard blow, the tappet in turn striking the drill steel 5'.
What is claimed is:—

65 A drill having a cylinder and a piston re-

ciprocal therein, there being passages leading to opposite ends of the cylinder, valve means on the piston for alternately directing motive fluid through said passages to the opposite ends of the cylinder, an auxiliary passage connecting the rear end of the cylinder with that one of said passages for conducting motive fluid to the forward end of the cylinder, an exhaust port in the cylinder arranged to be closed by the piston adjacent one end of its stroke, said port being arranged to be opened selectively to both ends by the piston.

In testimony whereof I affix my signature.

LOUIS W. GREVE.
